UNITED STATES PATENT OFFICE.

LOUIS H. HILL, OF MINNEAPOLIS, MINNESOTA.

GRAIN-DRIER.

1,123,877.

Specification of Letters Patent.

Patented Jan. 5, 1915.

Application filed February 17, 1914. Serial No. 819,203.

To all whom it may concern:

Be it known that I, LOUIS H. HILL, a citizen of the United States, and a resident of Minneapolis, in the county of Hennepin and State of Minnesota, have invented a new and useful Improvement in Grain-Driers, of which the following is a specification.

My invention is an improvement in grain driers, and has for its object to provide a device of the character specified, wherein mechanism is provided for passing the grain down an inclined rotating cylinder, provided with vanes extending longitudinally of the interior thereof for lifting portions of the grain to the top of the cylinder and dropping them, together with other means for forcing a current of heated air through the cylinder in the opposite direction to the movement of the grain.

In the drawings:—Figure 1 is a side view of the improved drier with parts in section, Fig. 2 is a top plan view, Fig. 3 is a detail sectional view of a portion of the drying cylinder showing the vanes, Figs. 4, 5 and 6 are sections on the lines 4—4, 5—5, and 6—6, respectively, looking in the direction of the arrows adjacent to the said lines.

The present embodiment of the invention comprises a body in the form of a plate 1, to which are connected front and rear axles 2 and 3 respectively, and braces 4 and 5 are arranged between the axles and the body. The rear axle is provided with wheels 6, and the front axle is provided with wheels 7, and a tongue 8 is connected to the axle for permitting the attachment of draft animals or apparatus for moving the machine.

A motor 9 of any desired construction, as for instance a liquid fuel engine, is supported by the body near the front axle, and the piston rod 10 of the said motor is connected to a crank 11 on a crank shaft 12, which is journaled in bearings 13 on the frame 14 of the motor. A fly wheel 15 is secured to the shaft outside of the frame, and a pulley 16 is secured to the shaft outside of the fly wheel. A belt 17 connects the pulley 16 with a pulley 18 on a shaft 19 supported by a bearing standard 20 arising from the plate or body 1. A beveled gear wheel 21 is secured to the shaft on the other side of the standards from the pulley, and a pinion 21^a on the lower end of a vertical shaft 22 meshes with the gear wheel. The

shaft 22 is supported by a bearing bracket 23, extending laterally from an arch bar 24, connected with the body, and the upper end of the shaft 22 extends above an arm 25 to be later described, the upper end of the shaft being journaled in the arm and in an overlying bearing arm 26 at the upper side of the arm. A wheel 27 is secured to the shaft between the arms 25 and 26, for a purpose to be presently described, and the said wheel 27 is designed to rotate the drying cylinder in the form of a casing 30, supported above the arm 25. The casing 30 is supported for rotation in bearing segments 31, one of the said segments being supported on the upper end of the arch bar 24 before mentioned, and the said segment carries the arm 25 just described. Each of the segments 30 is grooved on its inner face, and supporting wheels 32 are arranged in the grooves, the said wheels being supported by shafts 33, arranged transversely of the groove and engaged with the bearing ring at each side of the groove.

The casing 30 is provided with an annular guideway at each segment, each guideway consisting of a pair of laterally spaced rings 34, secured to the outer surface of the casing, and the wheels 32 fit between the rings and engage the outer face of the casing at this point. A ring 35 is secured to the casing adjacent to the wheel 27 before mentioned, and the said wheel engages one face of the ring, the other face being engaged by a wheel 36, journaled on a stub shaft 37 extending upwardly from a carriage 38, which is mounted to slide in a guideway 39, in the arm 25 before mentioned. A set screw 40 is engaged at its inner end with the carriage, the said screw being threaded through an upstanding lug 41 at the outer end of the guideway. It will be evident that by turning the screw, the counterpressure exerted by the wheel 36 as opposed to the wheel 27 may be varied. The wheel 27 rotates the casing 30 by its engagement with the face of the ring 35.

It will be noted from an inspection of Figs. 1 and 2 that the casing 30 inclines upwardly toward its rear end and also inclines inwardly. The front end of the casing is at the side of the plate 1, while the rear end is near the longitudinal center of the said plate. The bearing segment 31 at the front of the frame is as before stated,

on the arch bar 24, while the bearing segment at the rear of the frame is supported by a similar arch bar 24^a.

- 5 The front end of the casing 30 is closed by a head 42, and the casing is provided with an annular series of openings 43 near its forward end. An annular casing 44 is arranged on the casing 30 at the opening 43, and the said casing 44 fits the outer surface 10 of the casing 30 at opposite sides of the openings, so that anything passing through the openings 43 from the casing 30 would be received in the casing 44 and the said casing is provided with an outlet 45, extending 15 to the under face of the plate 1, at the side adjacent to the arch bar 24 and forwardly of the said arch bar. An expansion head in the form of a cylindrical casing 46 is arranged within the casing 30 at the casing 44, and the side walls of the said casing 46 are 20 perforate as shown. The casing 46 is of greater length than the casing 44 and extends beyond the respective ends of the said casing, and the said casing 46 is supported 25 co-axially with the casing 30. A pipe 47 extends from the front end of the casing 46 through the head 42 of the casing 30 at the center thereof, and thence downwardly as shown at 48 to near the upper surface of the 30 plate 1, and then rearwardly as shown at 49 to the casing 50 of a centrifugal fan or blower, the pipe opening into the fan casing tangentially as shown in Fig. 1. The fan 35 casing is provided with an axial inlet pipe 51, which extends into a heater 52, to be later described, supported on the body 1 at the rear axle. The pipe 51 opens into the heater 52 at the front end thereof and near the bottom and is then bent upwardly as 40 shown at 53 to near the top of the heater, where the said pipe is provided with a rearwardly extending inlet 54. The fan or blower (not shown) within the casing 50 is connected to the end of the shaft 19, which 45 extends into the casing, and it will be evident that when the said shaft is rotated, the fan or blower will be operated to withdraw air from the heater through the pipe 51—53—54, and to deliver it through the pipe 50 47—48—49.

55 A grate 55 is arranged transversely of the heater at the rear thereof, the said grate being spaced above the bottom plate 1 as shown more particularly in Fig. 6, and the heater is provided with a feeding chute 56 above the grate and at its rear end, and with a door 57 below the grate, the door 57 being for the removal of ashes and cinders, and the door 57 is provided with a damper as 60 shown at 58, in order that the draft may be regulated, and the side wall of the heater is provided with a series of openings 59 at each side below the grate.

65 The heater is of any preferred type and is designed to burn straw, wood or other

fuel, and the forward portion of the heater, (that portion in front of the arch bar 24^a) is a hot air chamber. A smoke stack 60 is provided at the front end of the heater for permitting the escape of smoke and the like. 70 The rear arch bar 24^a is braced at each side and in opposite directions by means of inclined braces 61 and 62, and a hopper 63 is arranged above the rear end of the casing 30, the said hopper having a feed chute 64 75 which opens into the rear end of the said casing.

The hopper is supported by brace bars 65 and 66, the bars 65 bearing at their lower ends against the outer surface of the heater 80 and the bars 66 being connected at their lower ends with the arch bar 24^a. The arch bars 24 and 24^a are of channel material as shown, and the rear bar 24^a is spaced above the top of the heater as shown more particularly in Fig. 6. A horizontal partition 55^a is arranged transversely above the feed opening 56, and below the inlet 54 of the fan. The front end of the partition is spaced apart from the front end of the 90 heater.

It will be noted from an inspection of Figs. 3, 5 and 6, that blades or vanes 67 are arranged within the casing 30, the said blades or vanes extending longitudinally of 95 the casing. Each blade or vane is provided with an angular portion 68 at one side edge which fits against the inner surface of the casing 30, and is secured thereto in any suitable manner, while the body of the blade or 100 vane extends into the interior of the casing. The vanes or blades extend in the same direction that the casing is rotated, and the said vanes or blades extend to near the expansion head 46 at their front ends. 105

The operation of the improved drier is as follows:—After a fire has been made in the heater to provide a sufficient supply of heated air, the motor 9 which may be of any desired character, is started. The grain or 110 other material to be dried is fed into the hopper 63 and passes by way of the chute 64 into the drying cylinder or casing 30, and since the said cylinder inclines downwardly toward its front or delivery end the grain 115 or other material will flow downwardly. The cylinder is rotating slowly, and as the grain flows downwardly through the cylinder, portions thereof will be lifted by the vanes and will be carried to the upper side 120 of the cylinder and will be dropped on to the bottom of the cylinder, and this lifting of portions of the grain to thoroughly mix and stir the same will continue until the grain has passed off of the lower ends of the vanes. While the cylinder is rotating heated air is 125 being withdrawn from the heater by the fan or blower, and the said air is being passed into the expansion head 46. The expansion head admits the heated air to the cylinder 130

in a uniform manner, and the heated air passes through the moving grain throughout the travel of the grain through the cylinder. As the grain nears the lower end of the 5 drier, it comes into closer and more intimate contact with the heated air issuing from the perforations of the expansion head, and the grain finally passes out by way of the openings 43 and the discharge pipe 45 into bags or other receiving means. The drying cylinder 30 is rotated from shaft 22, through the friction engagement of the wheel 27 with the ring 35. The weight of the cylinder is supported by the segmental bearing brackets or segments 31, and the tension between the wheel 27 and the ring 35 may be varied by means of the set screw 40. The grain will be thoroughly and uniformly dried during its passage through the 10 drying cylinder. The fan or blower is continuously withdrawing the heated air from the heater and forcing it through the grain in the drying cylinder. The vanes 67 are continuously lifting portions of the grain 15 to the top of the cylinder and discharging the said portions downwardly in the best possible manner, to subject the individual grains to the drying effect of the heated air. The feeding of the grain may be regulated 20 in accordance with conditions as for instance, in accordance with the conditions of the grain as regards moisture.

The machine, as a whole, is portable, and many changes might be made in the construction without departing from the spirit 25 of the invention. It will be noted from an inspection of Fig. 1 that the forward arch bar 24 is braced by inclined braces 69, the said braces extending from the plate or body 1 to the segmental bearing bracket.

The essential feature of the invention is the manner in which the grain is brought 30 into contact with the heated air in the drying cylinder.

45 I claim:—

1. A machine of the character specified, comprising a wheeled support, a heater on the support, a fan or blower having a connection with the heater for withdrawing 40 heated air therefrom, a drying chamber arranged above the support, said cylinder inclining upwardly and inwardly toward its rear end, arch bars arranged transversely of the support near the ends thereof, an arc-shaped bearing bracket on each arch bar, wheels journaled in each bracket, the cylinder having annular guideways in which the wheels are received for supporting the cylinder for rotating movement, a discharge 45 pipe leading from the fan to the lower end of the drying cylinder and extending into the said cylinder at the axis of the same, a perforate expansion head connected with the discharge pipe in the cylinder, an annular casing encircling the cylinder near

the lower end thereof, said cylinder having an annular series of openings for permitting the grain to pass from the cylinder into the annular casing, said casing having a discharge outlet, means for rotating the 70 drier, a motor on the support, and driving connections between the said motor, the fan and the rotating means of the cylinder, and vanes extending longitudinally of the interior of the cylinder for lifting the grain as 75 the cylinder rotates.

2. A machine of the character specified, comprising a wheeled support, arch bars arranged transversely of the support near the ends thereof, a bearing bracket on each 80 arch bar, a drying cylinder supported for rotation in the bearing brackets, said cylinder inclining upwardly toward its rear end, the cylinder having an annular series of discharge openings near its lower end, an 85 annular receiving casing encircling the cylinder at the openings for receiving the grain delivered through the openings, means for supplying heated air to the lower end of the cylinder, and a common means for rotating the cylinder and for operating the 90 heated air supplying means, an expansion head within the drying cylinder near the openings with which the heated air supplying means is connected, said head comprising 95 a substantially cylindrical casing supported coaxial with the drying cylinder and having a perforate wall.

3. A machine of the character specified, comprising a wheeled support, arch bars 100 arranged transversely of the support near the ends thereof, a bearing bracket on each arch bar, a drying cylinder supported for rotation in the bearing brackets, said cylinder inclining upwardly toward its rear end, 105 the cylinder having an annular series of discharge openings near its lower end, an annular receiving casing encircling the cylinder at the openings for receiving the grain delivered through the openings, means for 110 supplying heated air to the lower end of the cylinder, a common means for rotating the cylinder and for operating the heated air supplying means, and an expansion head within the drying cylinder near the 115 openings with which the heated air supplying means is connected.

4. A machine of the character specified, comprising a wheeled support, arch bars arranged transversely of the support near 120 the ends thereof, a bearing bracket on each arch bar, a drying cylinder supported for rotation in the bearing brackets, said cylinder inclining upwardly toward its rear end, the cylinder having an annular series 125 of discharge openings near its lower end, an annular receiving casing encircling the cylinder near the openings for receiving the grain delivered through the openings, means for supplying heated 130

air to the lower end of the cylinder, and a common means for rotating the cylinder and for operating the heated air supplying means.

5. In a machine of the character specified, a drying cylinder, means for supporting the cylinder for rotation on its axis and in inclined position, means at the upper end of the cylinder for feeding grain axially to the cylinder, means for rotating the cylinder, means for forcing heated air into the lower end of the cylinder, the cylinder having a discharge opening near the lower end, means at the opening for receiving the dried grain, and an expansion head within the cylinder at the lower end thereof to which the air forcing means delivers.

6. In a machine of the character specified, a drying cylinder, bearing brackets for supporting the cylinder for rotation on its axis, a driving shaft perpendicular to the axis of the cylinder, a ring secured to the periphery of the cylinder, a wheel secured to the shaft and engaging one face of the ring, a fixed support for the shaft at the wheel, a guideway on the support, a carriage movable on the guideway toward and from the shaft, a wheel journaled on the carriage and engaging the ring at the opposite side from the first-named wheel, and means for moving the carriage and holding it in adjusted position.

7. In a machine of the class described, in combination, a drying cylinder rotatably supported on an incline, a removable head fitting the lower end of said cylinder and

having a central opening therethrough, a pipe communicating with a suitable air supply and extending through the opening in the removable end of said cylinder and an expansion head secured to the end of said pipe within said cylinder formed substantially cylindrical and of perforated material.

8. In a machine of the class described, in combination, a pair of semi-circular brackets, a plurality of rollers journaled in each of said brackets and projecting beyond the inner peripheral face thereof, a drying cylinder having circumferential rings arranged in pairs, the rings of each pair fitting each side the rollers to each of said brackets, a friction ring secured circumferentially around said cylinder, a friction wheel bearing against one side face of said friction ring, means for rotating said friction wheel, and a friction roller adjustably arranged on the side face of said friction ring opposite said friction wheels.

9. In a machine of the class described, in combination, a drying cylinder rotatably supported on an incline, an expansion head of perforate material within the cylinder at the lower end thereof, and a pipe connected with the head and extending through the adjacent end of the cylinder at the center thereof, the cylinder being rotatable with respect to the pipe.
